[57] CLAIM

The ornamental design for a multiple table unit, substantially as shown and described.

DESCRIPTION

FIG. 1 is a perspective view of a multiple table unit embodying my new ornamental design;

FIG. 2 is a side elevational view of the multiple table unit of FIG. 1;

FIG. 3 is a top plan view of the multiple table unit of FIG. 1;

FIG. 4 is a bottom plan view of the multiple table unit of FIG. 1;

FIG. 5 is an end elevation view of the multiple table unit of FIG. 1 as viewed from the left-hand end of FIG. 2; and

FIG. 6 is an end elevation view of the multiple table unit of FIG. 1 as viewed from the right-hand end of FIG. 2.

The characteristic features of my design reside in the circular top in combination with the cylindrical legs highlighted by beading as seen on the legs and the tops.
